UNITED STATES PATENT OFFICE.

EDWIN L. DODSON AND HENRY GEORGE PELSTRING, OF COVINGTON, KENTUCKY.

FIGURE-TOY ATTACHMENT FOR DISK PHONOGRAHS.

1,294,243.

Specification of Letters Patent.

Patented Feb. 11, 1919.

Application filed September 9, 1918. Serial No. 253,160.

To all whom it may concern:

Be it known that we, EDWIN L. DODSON and HENRY GEORGE PELSTRING, both citizens of the United States, and residents of Covington, in the county of Kenton and State of Kentucky, have jointly invented a certain new and useful Improvement in Figure-Toy Attachments for Disk Phonographs, of which the following is a specification.

This invention relates to figure-toy attachments for disk phonographs, and more especially to removable attachments for use in connection with the disk-records to seemingly harmonize with the music being produced through the medium of said disk-records and the rotation of the latter being utilized in putting action into said figure-toy attachments to simulate dancing, jigging, acrobatic and other pleasing movements to entertain the observer while otherwise listening to the music or other accompaniment of the disk-records.

The special object and detail structure of the improvements herein will be defined in the description of the accompanying sheet of drawings, in which—

Figure 1 is a perspective view of a fragment of a phonograph, showing the upper part of the cabinet with the upper lid thrown partly open and with our invention herein in position for use; Fig. 2, a rear sectional elevation of the figure-toy attachment embodying our invention herein, showing a fragmentary part of the turn-table in section and, also, a fragmentary part of the upper sounding-board of the phonograph over which the said turn-table or disk-record holder is mounted for rotation; Fig. 3, a fragmentary section of the parts shown in Fig. 2, taken at a right-angle to said Fig. 2, and on the dotted-line *a*, *a*, of Fig. 2; Fig. 4, a sectional plan taken on the dotted-line *b*, *b*, of Fig. 2; Fig. 5, a diagram of the strip or piece of material used in the formation of the upright portion of the scaffold-support of the figure-toy; Fig. 6, a diagram of the strip or piece of material used in the preferred form of base-plate for attaching the scaffold to the upper sounding-board of the phonograph in operating

position; Fig. 7, a plan view of the guide device used by us in facilitating the accurate attachment of the said scaffold base-plate in place on the said sounding-board; and Fig. 8, a detail sectional view of the base-plate, showing the peculiar form of joint for detachably securing the lower end of the upright portion of the scaffold thereto.

1 indicates the upper part of the casing or cabinet of the phonograph; 2, the needle-carrier graphophone horn thereof; 3, the hinged cover or lid; 4, the rotary turn-table; 5, the tapered head at the upper end of the central stem or shaft 6, upon which head the said turn-table is mounted for rotation therewith over the sounding-board 7; and 8, the customary disk-record mounted on the turn-table and having its usual plain margin or border 9 outside the line of the etched or grooved record-portion 20 thereof.

We have shown in Fig. 1 the cover or lid part-way open, as it appears in the use of the phonograph when the figure-toy attachment is in observing and performing place.

Thus far we have described but the ordinary form of phonograph in general use and we will now take up the details of the preferred form of figure-toy attachment for use in connection with the machine to add visible to its audible purposes of entertainment and amusement.

10 indicates the upright portion of a scaffold or pedestal and 11 the horizontal attaching base-plate thereof, a pair of small holes 12 being provided in the latter to accommodate short vertical screws 13 that secure it to the sounding-board 7 in readily detachable position so that said upright portion 10 may be properly held and distanced from the peripheral edge of the turntable 4 to suit the presence and operation of the figure-toy devices comprising the main features of the invention and to which we will now refer in detail.

The base-plate 11 being provided, as above stated, with a pair of small holes 12, a removable guide-card or gage-sheet 14, such as is best shown in Fig. 7, is preferably used to facilitate the accurate setting and securing of the base-plate in place on

the sounding-board 7 so that it shall bear the proper relation to the front position of the peripheral edge of the turn-table 4 in supporting the upright portion 10 of the scaffold for the desired working of the figure-toy devices.

The said guide-card 14 is provided with each figure-toy device for use with a phonograph in setting up the figure-toy in proper position, as above stated, and it has a hole 15 that freely engages the cylindrical base of the tapered head 5 at the upper end of the disk driving-shaft 6, for its ready handling to and from position on the sounding-board 7. Holes 16 are made near the fore end of the guide-card to serve as ready means in the making of holes or dots on the surface of the sounding-board to suit the exact position of the screw-holes 12 in the base-plate 11, the said holes 16 and the holes 12 duly registering when the guide-card has been used.

An arrow or pointer 17 is preferably printed or otherwise produced on the surface of the guide-card, to accurately point to the front of the turn-table and thereby centralize the said guide-card for the proper and speedy setting of the said base-plate 11. The guide-card can be easily removed from the sounding-board and the shaft-head 5 after the holes 12 for the fastening-screws 13 of the base-plate have been marked or punched through the guide-holes 16, (perforated-pattern like), and then the turn-table can be properly set on its tapered driving shaft-head 5 for operation through the medium of the customary power or motor mechanism located within the casing or cabinet of the phonograph.

18 indicates a pair of minute holes made in the guide-card to the rear of the pair of similar holes 16, and 19 is a dotted-line or the like printed or otherwise produced on the surface of the said guide-card intermediate the pairs of holes 16 and 18, the purpose thereof being hereinafter more fully referred to. The remainder of the surface of the guide-card 14 may be used for the printing of necessary directions thereon for the mounting of the base-plate and scaffold and the operation of the figure-toy device otherwise, but not shown on the card in the drawings.

In Figs. 5 and 6 we have best shown the structure of the scaffold, including both its upright portion and the attaching base-plate. These two members are preferably made of sheet-metal that is light and sufficiently strong to suitably mount the figure-toys. The upright portion 10 is struck up with vertical side edges 21 that are bent over along the dotted-lines 21^a to form stiffening flanges that are adapted to support a vertically adjustable and removable perform-

ance-stage or dancing-platform 22, also 65 made of sheet-metal and having down-turned flanges 23 together with folded or bent-over clips 24, the latter for engagement with the said flanges 21 along the opposite edges of the upright 10, free enough to be 70 slid up or down to suit the desired height of the stage or dancing-platform above the plane of the turn-table 4. Square portions 25 are cut out along three sides thereof in the metal from just below the middle to a 75 point near the upper end of the upright 10, staggered fashion, and each adapted to be bent along the dotted-lines 26 and 27 to form inwardly-flanged arms 28, two at either side of the vertical center of the upright 10, the 80 purpose of which will be shortly referred to. The lower end of the upright 10 is cut to form shallow feet 29 and with laterally-projecting tongues 30, the latter being adapted to enter the slots 31 made in the 85 lower ends of the vertical side flanges 21 after the said lower end of the upright 10 has been bent along the dotted-lines 32 into a horizontal flange or base-support 33, and then said tongues 30 bent over to lock the 90 base-support and side flanges of the upright 10 into firm and substantial corners. Between the said dotted-lines 32 we make a three-sided cut in the metal that becomes a central foot 34 for the base-support 33, it 95 projecting in an opposite direction to that of the feet 29 and to be applied as we shall now proceed in connection with the structure of the base-plate 11. Three L-shaped cuts are made in the base-plate 11, as best shown 100 in Fig. 6, one long cut 35 being at the fore center thereof, and the other two 36, 36 being short ones at approximately the longitudinal center of the plate. These cuts are disposed toward each other and are adapted 105 to be upset or upwardly bent along the dotted-lines 36^a so as to accommodate thereunder the shallow feet 29 and the central foot 34 of the scaffold upright 10, whereby 110 what may be termed a bayonet-connection is 115 made between the lower end of the said upright 10 and the said supporting and attaching base-plate 11, the upright 10 being slid sidewise along the face of the base-plate 120 so that said feet 29 and 34 shall enter and 115 duly wedge beneath the said upset or overhanging parts 36 and 35, respectively, of the cuts, after the lower end of the upright 10 has been inserted, first, from the sides of the 125 upset cuts and then anchored against further movement by the obstructions presented by the vertical end walls or bends made in the cut-out portions of the metal for securing the said upright to the said base-plate in a readily detachable position.

The figure-toy 37 is a flexible-jointed one of any desired make-up or character, conventional, whimsical, grotesque, or other-

wise, and is preferably composed of a tough card or like stiff material, with a main upper portion 38, a middle or upper leg portion 39, and a lower leg portion 40, the latter having feet that are adapted to dangle or move freely upon and over the vertically-adjustable stage or platform 22, as best shown in Fig. 3. The back of the main portion 38 of the figure-toy is provided with a rearwardly-projecting, angular, supporting flange-clip 41 whose upper horizontal member or flange is adapted to engage a pair of spring jaws 42 of the forwardly-projecting plate 43 that is fastened to the top of the vertical slide-bar 44 by means of small nails or screws, the said slide-bar having grooves or slits 45 cut centrally along its vertical side edges to form guide-ways therein for the up and down reciprocations of the said slide-bar 44, the inwardly-flanged arms 28 on the back of the upright portion 10 of the scaffold quite freely engaging the said slits 45 and forming guide-ways along either side of said slide-bar so that it may freely carry the figure-toy up and down along the front of the upright 10, but without touching it, and said scaffold front being capable of presenting an attractive background for the figure-toy when suitably decorated or surfaced. The feet of the figure-toy duly touch the platform at times, but not essentially so, whereby the joints of the toy are caused to turn or bend and then for the legs to be thrown laterally and up and down in all sorts of paths to perform many comical and peculiar movements to add visible entertainment to the listener who is also in close sight thereof.

An eccentric 46 is mounted on a pin or stud 47 near the lower end of the slide-bar 44, as best shown in Figs. 2 and 3, and the periphery of the eccentric is preferably girdled with a rubber tire or band 48 for noiseless and frictional engagement, in operation, with the smooth or plane edge or margin 9 of the disk-record, or in connection with the peripheral edge of the turn-table itself in the event it is desired to operate the toy with a record of small diameter or without any disk-record on the turn-table at all.

The use of the removable gage or guide card 14 facilitates the accurate setting or placing of the scaffold base-plate at its extreme outermost position, as shown in Fig. 3 for turn-tables of the largest diameter, or the scaffold base-plate can be mounted nearer the center pin or shaft by using the dotted-line 19 on the guide-card as a guide to be used in the exact placing of said base-plate for turn-tables of lesser diameter, and then the pairs of holes 16 or 18, as the case may be, in the guide-card then used to easily puncture or prepare places or marks for holes in the sounding-board to accommodate

the attaching-screws, to suit the diameter of 65 turn-table or disk-record.

In Fig. 3 we have shown the device in its high position, the eccentric being with the widest part of its axial diameter lowermost in its revolution, and with the feet of the figure-toy just touching or resting on the platform 22, which latter has been adjusted to suit that initial position of the little figure-toy or dancer. As the turn-table and its accompanying disk-record advance in 75 their rotations the eccentric is made to frictionally contact and turn therewith along the smooth or plane margin of the disk-record, whereby the slide-bar is carried up and down at quite a high speed, commensurate or timed with that of said disk-record and its turn-table, the latter being speeded to suit the piece of music being played and the figure-toy or dancer, in turn, to move in seeming harmony therewith, flinging its legs 80 and arms in various directions in simulation of the living dancer or other subject being imitated, and to afford much merriment and amusement.

It will be observed that the device is a 90 "knock-down" affair capable of packing in small compass in boxes for sale or for keeping when not in use.

We claim:

1. A figure-toy attachment for a phonograph comprising an upright scaffold adapted to be secured to the sounding-board of the phonograph in juxtaposition to the peripheral edge of the disk-record turn-table, a figure-toy, a slide-bar upon which the said figure-toy is mounted, guide-ways on the back of the upright scaffold for the vertical reciprocations of the said slide-bar, a miniature performance-stage or platform on the said scaffold for the accommodation of the 100 said figure-toy, and an eccentric roller that is mounted on the said slide-bar for frictional engagement with or without the disk-record on the turn-table whereby the figure-toy is caused to vibrate or perform. 110

2. A figure-toy attachment for a phonograph comprising an upright scaffold-member, a detachable base-plate on the sounding-board to which said upright scaffold-member is detachably secured, a stage or platform adjustably mounted on the said scaffold-member for the accommodation of the figure-toy, a slide-bar moving in guide-ways on the back of the said scaffold-member, a figure-toy detachably mounted under resilient or spring tension at the top of the said slide-bar so as to vibrate or perform over and upon the said platform, guide-ways in the slide-bar, an eccentric roller mounted at the lower end of the said slide-bar and girdled or faced with a rubber band or tire, a turn-table under motor or power driven mechanism, a disk-record mounted 115 120 125

on the said turn-table and adapted to have driving-contact with the said rubber-faced eccentric for the rotations of the latter on the smooth or plane margin or border of the 5 face of the disk-record and to drive or reciprocate the slide-bar vertically for causing the vibratory performance of the figure-toy

on the platform, and means for facilitating the accurate gaging and setting of the said detachable base-plate of the scaffold-member in proper mounted position on the sound-board of the phonograph. 10

EDWIN L. DODSON.
HENRY GEORGE PELSTRING.
